This is a continuation of my application, Serial No. 665,965, filed April 30, 1946, now pending.

One of the objects of my invention is the provision of a window structure which may be either installed in a window opening or installed in the usual window frame as for instance in connection with storm windows, from which the sash are usually removed in warm weather.

UNITED STATES PATENT OFFICE

2,574,742

WINDOW STRUCTURE

Augustine John Kiefer, Pittsburgh, Pa.

Application April 30, 1946, Serial No. 665,965

1 Claim. (Cl. 20—52.2)

1 My invention consists in a new and improved window structure, including a frame and sash slidably mounted therein.

One of the objects of my invention is the provision of a window structure of frame and sliding sash which may be either installed in a window opening or installed in the usual window frame as for instance in connection with storm windows, from which the sash are usually removed in warm weather.

Another object is the provision of means for sustaining the sash in the frame at a selected elevation without the use of counterbalancing means such as cords and weights.

Another object is the provision of means for installing the sash in the frame and removing them therefrom quickly and conveniently and without the use of tools.

Another object is the provision of a window structure in which the windows may be mounted to slide easily where the frame is out of true.

Other objects will appear from the following description.

In the accompanying drawings, wherein is illustrated a practical embodiment of the principles of the invention,

Fig. 1 is an inside elevation of a window to which the invention is applied;

Fig. 2 is a broken perspective of one of the auxiliary window stiles, interior parts being indicated in dotted lines;

Fig. 3 is an enlarged vertical section taken along the line 3—3 in Fig. 1 showing the lintel portion of the window frame, the inner window frame, in the illustrated embodiment of the invention;

Fig. 4 is a similar view taken along the line 4—4 in Fig. 1, showing the sill portion of the same;

Fig. 5 is a similar view taken along the line 5—5 in Fig. 1 showing the relation of the meeting rails of the upper and lower sash;

Fig. 6 is a fragmentary perspective of the meeting rail of the lower sash;

Fig. 7 is a perspective of the meeting rail of the upper sash;

Fig. 8 is an enlarged horizontal section taken along the line 8—8 in Fig. 1 illustrating the method of mounting the sash in place and dismounting it therefrom;

Fig. 9 is a view illustrating several forms for the interengaging edges of the sash and the combination packing and parting strip member.

Referring to the drawings, the window open-

ing as illustrated in Fig. 1 is provided with the conventional stationary window frame comprising the sill 10, the lintel 11, and the vertical stiles 12.

Within the stationary frame there is installed, preferably removably, an inner window frame, which may be formed conveniently of sheet metal, and which comprises a sill 13, a lintel 14 and the vertical auxiliary stiles 15.

10 The sill 13 and the lintel 14 may be, as shown in Figs. 3 and 4 respectively, of similar cross sectional form but inversely disposed.

Thus the sill 13 is provided along its top surface with a pair of parallel vertical flanges extending longitudinally of the sill, the flange 16 extending along the inner side of the sill and the flange 17 parallel with flange 16 but spaced therefrom. When the lower sash 18 of the window is in its closed position, as indicated in Fig. 4, the outer vertical surface of the bottom bar 19 of the sash snugly engages the inner vertical face of the flange 16 while the flange 17 is telescoped from above by the slot 20 formed in the lower face of the sash bar 19, thus forming a weather seal between the sash and the sill 13. To deflect rain the top wall of the sill 13 preferably is inclined downwardly from the flange 17 to the outer edge of the sill.

15 20 The lintel 14 of the inner frame is disposed in a position the reverse of that of the sill 13, the flange 16 being at the outer side, as illustrated in Fig. 3, and when the upper sash 21 is closed the face of the flange 16 fits against the vertical face of the top bar 22 of the upper sash, while the flange 17 engages a slot 23 in said bar, thus forming a weather tight seal between the sash and the lintel.

25 Referring now to Figs. 5, 6 and 7, 24 indicates the meeting rail of the lower sash 18, and 25 the meeting rail of the top sash 21. These rails are of greater thickness than the lower bar of the lower sash and the upper bar of the upper sash, thus bridging the space between the sash corresponding to the combined width of the parting strip sections of the stile later to be described.

30 The lower portion of the outer face of the meeting rail 24 is cut away to form a recess 26 to provide clearance, when the sash are closed and the meeting rails are in their relative positions shown in Fig. 5, for the inner extending trough-like extension 27 of the rail 25.

35 28 indicates a resilient metal packing strip having a hook-shape cross section, attached at

its upper portion to the inner face of rail 25 and depending within the trough of extension 27, while 29 indicates a like packing strip attached to the outer face of rail 24 and extending down within the recess so as to engage and nest in the packing strip 28 as shown in Fig. 5, when the sash are both in their closed position.

Adjacent each end of the sill 13 and of the lintel 14, the flanges 16 and 17 are omitted so that the ends of the sill and lintel may be telescoped into the auxiliary stiles 15 and be secured therein as by welding or riveting. Likewise the extra width of the meeting rails of the lower and upper sash is reduced to the width of the bars 19 and 22, to provide clearance for the parting strip sections, as indicated at 30 in Figs. 6 and 7.

The auxiliary stiles 15 may be formed conveniently by bending up a strip of metal of the proper length and width to a rectangular cross sectional shape comprising a closed rear wall, parallel side walls and an open front.

The inner frame formed by the sill 13, the lintel 14 and the auxiliary stiles 15, connected together at their extremities is of the proper exterior dimensions as to fit in the outer window frame or window opening, as the case may be, and may be held in position by any convenient means such as resting inwardly of the building against the vertical strips 31 secured to faces of the stiles 12, as by means of the screws 32 extending from without through the spaced side walls of the auxiliary stiles 15 and driven into the strips 31.

Adjacent their outer vertical edges the side walls of the auxiliary stiles 15 are provided with internal shoulders or stops 33, which when the auxiliary stiles are formed of sheet metal, may be produced by folding the metal inwardly and backwardly against the inner surfaces of the side walls as shown in Figs. 2 and 8.

34 indicates a metal bar mounted in the interior of each of the auxiliary stiles 15 and extending longitudinally therein in front of the screws 32. The bars 34 are of T-cross sectional shape, the stem 35 of the T extending toward the open fronts of the auxiliary stiles, and the base of the stem being enlarged laterally to form a double stop 36.

37 indicates a pair of bars mounted in each of the auxiliary stiles 15, one on either side of the stem 35 of the bar 34 and each provided at its rear vertical edge with flanges 38 projecting laterally to either side, one of said flanges limiting the outward movement of the member relative to the bar 34 by contact with the stop 36, while the opposite flange 38 by engagement with the stop 33 prevents accidental disassemblage of the parts relative to the auxiliary stile.

The members 37 are elongated bars extending up through the auxiliary stiles, and they are urged outwardly to protrude from the open fronts of the auxiliary stiles by a vertical series of bowed leaf springs 39 riveted or otherwise secured at their centers to the front face of the bar 34 with their ends bearing against the backs of the members 37.

The front edges of the members 37 are provided centrally with a vertical bead 40 which engages vertical slots 41 in the edge of the sash, thus slidably supporting the sash in the frame.

The members 37 are also provided with offset shoulders 42 which mate in pairs, as shown in Fig. 2 to form a sectional parting strip between the upper and lower sash, the parting strip sections 42 moving inwardly and outwardly in unison

with the beads 40, both being portions of the corresponding members 37.

It is thus seen that the upper and lower sash are mounted for vertical sliding movement on either side of the sectional parting strips.

If desired, the sliding connection between the members 37 and the sash, instead of being a bead and groove, may be formed of arcuate or angular convex and concave surfaces of the member 37 and the edge of the sash as indicated in Fig. 9.

Fig. 8 illustrates the method of installing a sash, in the illustration the lower sash 18, in the frame. The sash is first presented in the horizontally tilted position shown and one of its grooved edges, the left in the view, is engaged with the bead 40 and the sash is then pushed to the left until the member 37 is caused to retreat sufficiently into its auxiliary stile to permit the window to be swung inwardly to engage the groove 41 on the right hand edge of the window with the bead 40 on the corresponding member 37. The leaf springs at either side will then automatically center the sash in position. In installing the sash, the upper sash is first put into position.

25 The removal of a sash is accomplished by reversing the above-described operation, the sash being first pushed in one direction to retreat the corresponding member 37 sufficiently to permit the other edge of the sash to be released and the sash is then lifted out. In removing the sash the lower one is first removed.

20 The forming of the parting strip of two cooperating sections, each moving with the member 37, renders the insertion of a sash into and its removal from the frame much more easy as there is no chance of the sash jamming against a stationary parting strip.

25 The pressure of the springs 39 act to hold the sash in position without the use of counterbalance means such as cords and weights.

30 While the invention is particularly advantageous for the installation of storm windows, the inner frame being mounted in the permanent window frame as illustrated in the drawings, the frame hereinbefore referred to as the "inner frame," formed of the sill 13, the lintel 14 and the auxiliary stiles 15, may be installed in any window opening in the absence of a permanent window frame.

35 Screen sashes may be substituted for the window sash shown.

40 While the sash shown are of wood, the same may be of metal or other suitable material, and wood may be used as the material of the frame and associated parts.

45 It is evident from the above that my invention provides an inexpensive yet substantial and durable window structure, wherein the sash, screens, or other sliding closures may be readily installed and removed when desired.

50 It is also apparent that by means of the present invention sliding windows may be successfully inset in a frame which is distorted so as to be out of line, owing to the flexibility of the means 55 for mounting the sash in the frame.

I claim:

55 A window sash attachment comprising opposed stiles in the form of inwardly open channels constructed to be secured to a permanent window frame, a bar of T-shaped cross section dividing each of said channels into like vertical cavities with the T-head bar being shorter than the depth of the channel to form a stop, an auxiliary stile mounted in each cavity and each having a bead to fit and guide a window sash, resilient means to

urge said auxiliary stiles outwardly of the channel against a window sash, an offset shoulder on each of the adjacent sides of the auxiliary stiles in each channel which offset shoulders mate in pairs to lie against each other to seal and form a sectional parting strip, and a flange extending from adjacent the rear edge of each auxiliary stile and in alignment with its offset shoulder, said offset shoulder and flange of each auxiliary stile co-operating with said T-head stop to limit the inward and outward movement of the auxiliary stile in the channel.

AUGUSTINE JOHN KIEFER.
